UNITED STATES PATENT OFFICE.

CHARLES W. DENNIS, OF BROOKLYN, NEW YORK, ASSIGNOR TO METAL PACKAGE COMPANY, OF BROOKLYN, NEW YORK, A CORPORATION OF NEW YORK.

BOX.

1,205,519.

Specification of Letters Patent.

Patented Nov. 21, 1916.

Application filed February 23, 1916. Serial No. 79,857.

To all whom it may concern:

Be it known that I, CHARLES W. DENNIS, a citizen of the United States, and a resident of Brooklyn, in the county of Kings and State of New York, have invented certain new and useful Improvements in Boxes, of which the following is a specification.

My invention relates to boxes or containers for food or other products and its object 10 is to provide a sanitary box or container affording a perfect substitute for boxes or containers made of cardboard and which shall be at the same time cheap, light, afford a perfect protection for the contents of the 15 box and have all the ornamental appearance of the ordinary pasteboard box.

To these ends my invention consists in a box of combined metal and paper constructed as hereinafter more particularly described 20 and then specified in the claims.

In the accompanying drawings Figure 1 is a perspective view of a box constructed in accordance with my invention, the body and cover being shown in cross-section. Fig. 25 2 is a cross-section of a box constructed in accordance with my invention and showing the manner of providing an ornamental line at the corner of the cover. Fig. 3 is a cross-section of a box constructed in accordance 30 with my invention and having an extension top and bottom.

2 indicates the cover and 1 the body of the box. The foundation or base portion of each is thin sheet metal indicated in the 35 cross-section at 3 and made up into the required form in any desired manner.

In the preferred manner of carrying out my invention the sheet metal base or foundation is provided with a bead indicated at 40 extending clear around the body near the top edge thereof. The sheet metal of the base both in the body portion and in the cover portion of the box is coated on the inside with a sanitary lacquer such as is 45 prescribed by the pure food commission and said lacquer may, if desired, be applied also to the outside of the sheet metal base, such application of the sanitary lacquer being preferably made before the sheet metal is 50 formed up to make the body and cover although, so far as the inside is concerned, it might be applied after the attachment of the layer or coat of paper or other fabric covering the outside of the box and cover. Such 55 sanitary lacquer coating serves the same pur-

pose as the ordinary sanitary lining of paper and also in my improved construction of box may be applied to aid in attaching the paper coating, in which case it forms a base for the adhesive, increasing the 60 bond.

5 indicates a layer or coating of paper or similar fabric closely adhering to the metal base, for which purpose it may be cemented to the surface of the metal by glue or other 65 suitable material. Said paper coating or surface may have the texture and appearance of the ordinary paper surface of cardboard boxes and obviously may vary according to the taste of the designer. As shown 70 in Fig. 5, the paper layer or coating 5 is applied over the whole metal body of the box and covers the metal joints, if any, at the corners thereof, but preferably in such manner as to leave the metal bead 4 of the 75 metal base exposed. At the top edge of the metal base forming the body the paper coating extends over the raw metal edge and a suitable distance on the inner surface of the metal base to form a good attachment. In 80 a similar way the paper coating or layer 5 upon the cover extends around the raw metal edge of the sheet metal and up on the inside of the flange or skirt of the cover to any desired distance, as clearly shown in the 85 drawing. The exposed metal of the sheet metal base along the line of the uncovered bead affords a line of ornamentation similar to that obtained in ordinary pasteboard boxes by pasting on a strip of gold-sized 90 paper. The metal effect is enhanced by the sanitary lacquer adhering to the bead when the metal box is dipped in the sanitary lacquer previously to the application of the paper coating. Obviously gold or other metal 95 lacquer might be applied to the metal of the bead but usually, for the sake of cheapness, it is desirable to depend upon the effect of the sheet metal itself having the coating of 100 sanitary lacquer. The lip or edge of the cover preferably extends down to engage the bead 4, the bead thus forming a stop and coöoperating with the edge of the cover to form a seal by the engagement of the 105 soft paper edge with the metal bead. The sanitary lacquer of the sheet metal base not only affords a sanitary lining much superior to paper lining but the lacquer may also form as before stated, a base for the cement or adhesive like glue, used for attaching the 110

paper surface to the metal base, and thereby increases the bond.

The bead not only forms a stop and a line of ornamentation when left exposed and treated as described, but also stiffens the box. As illustrated in Fig. 2, a line of exposed metal of the sheet metal base may be formed on the cover at the edge thereof, a break being left in the paper coating along such line, as indicated at the point 9. This line of exposed metal will form an ornamentation similar to that secured in pasteboard boxes by applying a strip of ornamental paper, the sheet metal exposed having, if desired, the coating of sanitary lacquer to enhance the effect or being otherwise treated or ornamented preferably before the application of the paper coating. As will be seen, the paper coating being extended over the edge of the sheet metal base constituting the base for the body and cover, will protect the raw edge of the metal which, in ordinary packages or boxes of sheet metal having a paper wrapper, is left unprotected and frequently is so sharp as to injure the hand of the user.

By my invention I afford a perfect substitute in every respect for the ordinary pasteboard box or container while at the same time I secure, without added cost, additional advantages, as already set forth, over the ordinary pasteboard box.

As a box or container for candy my improved construction affords a cheap and practical substitute for the ordinary pasteboard box inasmuch as it may be readily made as highly ornamental as a box of pasteboard while moreover the sheet metal presents no raw edges, and further, the package preserves the contents and keeps them fresh, which it is impossible to do with the ordinary pasteboard containers for candy, a fact well recognized in shipping boxes of candy since, as is well known, the practice is to slip the pasteboard box into an outside container of metal to preserve the contents of the pasteboard box.

A package constructed in accordance with my invention accomplishes the purposes of two boxes ordinarily employed in shipping candy.

An additional advantage secured by my invention is that inasmuch as the protected paper edge of the sheet metal base forming the cover, by abutting against the bead on the body, forms a better seal than could be afforded by the metal to metal contact as found in the ordinary construction of metal boxes, it is therefore not necessary to paste the paper over the meeting edge of the body and cover after the cover has been put in place, as is frequently done in order to seal the contents in an ordinary metal box.

Referring to Fig. 3, the body and cover are each shown provided with an extension

edge. In this instance a paper coating is applied over a sheet of cardboard or other material 8 and said coating is carried, in the case of the body, preferably only part way up the side of the metal base and properly cemented thereto, while the paper coating of the body is preferably carried down over the edge of said paper coating for the plate 8. In the case of the cover a similar sheet of cardboard or other material 8' is applied to the cover and is provided with a coating or layer of paper or other substance carried around the edge of the plate 8' and cemented to the layer or coating 5 of paper applied to the metal base of the cover and extended partially over the top thereof as clearly shown. Between the top of the plate 8' and the paper cover thereof a padding indicated at 10 may be inserted to give the effect of a padded cover.

What I claim as my invention is:

1. A box or container made on a sheet metal foundation having a closely adherent surface or coating of paper or similar fabric cemented to the surface of the metal in a manner to leave a continuous band-like line of exposed metal the bounding edges of which are the edges of the cemented surface coating of paper.

2. A compound box or container consisting essentially of a sheet metal base and closely adherent coating or surface of paper cemented to the surface of the metal, the body of the box being provided on its side between the top and bottom edges with a continuous bead consisting of the exposed metal of the sheet metal base exposed between edges of the paper coating upon the same plane surface as and for the purpose described.

3. A compound box or container of sheet metal and paper comprising a sheet metal base having a closely adherent coating of paper cemented to the exterior thereof, the sheet metal for the body of the box or container being provided with a continuous bead of exposed metal and the cover of the box having its paper surface extended around the edge of the cover and adapted to engage said bead.

4. A compound box or container composed essentially of sheet metal and paper, the sheet metal forming the base and being provided with a sanitary lining consisting of a sanitary lacquer while the paper constitutes a closely adherent coating cemented to the surface of the sheet metal base.

5. A compound box or container composed of sheet metal and paper, the sheet metal being provided with a sanitary lacquer and the paper constituting a closely adherent coating cemented to a lacquered surface of the sheet metal as and for the purpose described.

6. A box or container the cover of which

comprises essentially a foundation of sheet metal and a closely adherent coating of paper cemented to the surface thereof and extending over the top surface of the cover
 5 part combined with a false or extension top or bottom comprising a plate of cardboard or other suitable material having padding on its top and an inclosing layer inclosing said padding and extending around the edge
 10 of the cardboard and the lower surface thereof and cemented to the paper coating of the metal cover.

7. A box or container having a cover comprising essentially a foundation of sheet metal provided with a closely adherent paper coating cemented to the exposed surface thereof and extended over on to the top of the foundation combined with an extension top consisting of a coated plate the
 20 coating of which extends around the edge of said plate on to the lower surface thereof to a sufficient extent to engage the extended coating of the sheet metal foundation and cement it to the latter coating as and for the
 25 purpose described.

8. A box or container the cover of which

consists essentially of a sheet metal foundation having a closely adherent coating of paper cemented upon the exposed surface and extended around the edge of the sheet
 30 metal forming the edge of the cover as well as partially over the top, combined with a plate of cardboard or similar material provided with an elastic cushion and having an inclosure composed of paper which extends around the edge of the cardboard and on to the lower surface and cemented to said surface as well as to the surface of the paper coating for the metal foundation.

9. A sanitary box or container comprising
 40 essentially a sheet metal base and a closely adherent outer layer or surface of paper cemented to the sheet metal, the metal on the inside of the box being exposed and coated with a sanitary lacquer.

Signed at New York in the county of New York and State of New York this 21st day of February, A. D. 1916.

CHARLES W. DENNIS.
